 Transit Research Corporation, New York, N. Y.,
 a corporation of New York

Application March 27, 1937, Serial No. 133,477

5 Claims. (Cl. 105—451)

This invention relates to public conveyances such as street cars and buses, and especially to electrically operated conveyances intended to be used in those parts of the world in which snow is encountered during a portion of each year.

During the operation of street cars in snowy weather, it has been found that entering passengers carry into the cars a certain amount of snow upon their feet. Some of this snow drops off or is scraped off onto the steps as they enter the car. Some passengers stamp their feet to remove it as they enter. When snow is falling and the wind is blowing against the entrance side of the car, it is frequently blown in when the door is open to admit passengers. Sometimes the snow drifts in also under the lower edge of the door when the door is closed. It is trampled upon and packed down by the incoming passengers turning into ice, and on some days builds up to a considerable depth. This packed snow and ice makes the footing of incoming passengers less secure and causes them to enter the car more slowly, thus slowing down the operation of the car. Occasionally, a passenger slips upon the slippery surface and injures himself. In severe weather it sometimes becomes thick enough to interfere with or sometimes prevent entirely the operation of the doors, which in the more modern cars are arranged to swing inside of the car.

One of the principal objects of this invention is to provide a means for preventing such an accumulation of snow or ice.

More specifically it is an object of this invention to provide means for melting the snow or ice upon the steps as rapidly as it accumulates. Another specific object is to employ a portion of the car heating system as a means for directing a warm stream of air over some of the steps upon which such accumulation would ordinarily occur.

Another object is to provide a body comprising sills, cross-sills and pier posts of hollow construction to constitute ducts for warm air, and to extend these ducts beneath a step in such manner that the extensions also constitute body structural members.

Other objects and advantages will become hereinafter more fully apparent, as reference is had to the accompanying drawing, wherein my invention is illustrated and in which,

Fig. 1 is a diagrammatic perspective view of the parts of the car necessary for a clear understanding of this invention, with parts broken away to more clearly show their structure,

Fig. 2 is a diagrammatic sectional view taken upon a plane just below the floor of the car.

Fig. 3 is a sectional view on the line 3—3 of Fig. 2, taken in the direction of the arrows, and

Fig. 4 is a sectional view on the line 4—4 taken in the direction of the arrows.

While this invention is applicable to any type of street car or to buses or other vehicles, I have chosen to illustrate it in connection with the most modern type of street car having a heating system of the type disclosed in the co-pending application of Emil H. Piron, Serial No. 84,732, and having, with this application, a common assignee. In this form of street car, the side sills 10 and 11, the cross sills 12, 13, 14, and 15, and 15 the pier posts 16, 17, 18, 19, 20, 21, 22 and 23, which form a large part of the frame of the car, are hollow box-section members most of which are used as ducts to constitute the collection and distributing means for a heating and ventilating 20 system.

The space under the floor 24 of the car between the two central cross sills 13 and 14 contains the air heating and impelling means for the system. In this space, on the side of the 25 car opposite the steps 25 and 26, is placed the blower 27 which circulates the air. In cold weather, air supplied to the blower 27 is collected through openings 28 and conducted into the space between the ceiling 29 and the roof 30. 30 From this space it passes down through the pier posts 16, 17, 19, 21, 22 and 23, and through the end cross sills 12 and 15 to the side sill 11. The side sill 11, which projects slightly above the floor 31 of the car 24, is also provided with apertures 31 35 opening directly into the interior of the car just above the floor 24. Air is also withdrawn from the interior of the car through these apertures 31 and joins the air collected through the apertures 28. 40

From the side sill 11, the collected air is led through blocked off portions of the center cross sills 13 and 14 to a chamber 32 containing the blower 27. From this chamber 32, the air is forced by the blower 27 into a second chamber 45 33 containing resistances 34 which heat the air. In the embodiment of the invention illustrated, the resistances 34 are used for controlling the traction motors 41, only one of which is shown in the diagram. It will be understood that, in 50 the case of a rail vehicle, the motors are carried by trucks, not shown.

The heated air then flows from the chamber 33 through the cross sills 13 and 14 to the side sill 10 which serves as a distribution duct. The 55

side sill 10 projects slightly above the floor 24 and is provided with a series of apertures 35 out of which the warm air can flow into the interior of the car. Dampers 36 are provided in the walls 5 of the cross sills 13 and 14 to send the warm air to the outside of the car instead of to the inside as may be desired. These dampers 36 are controlled manually or by suitable thermostatic means, so that the temperature of the interior 10 of the car is maintained within a given range. In severe winter weather, when the heat provided by the motor resistors 34 is not sufficient to heat the car, additional heat is provided by extra resistances 37 placed in the side sill 10 15 which serves as the warm air duct. The passage of current through the extra resistances 37 is also controlled by suitable thermostatic means.

It will be noted that in the heating and ventilating system as described thus far, warm air is 20 conducted by the cross sills 13 and 14 to both ends of the steps 25 and 26 at the center of the car, and that warm air is conducted by the side sill 10 to the rear end of the front steps 38 and 39. My invention contemplates the use of this 25 warm air in any manner to melt snow that may accumulate upon the steps 25, 26, 38, or 39. This may be accomplished by extending the air ducts under the steps so as to heat the steps 25, 26, 38 and 39 from underneath. A more effective means 30 is to direct warm air, either from the end of the steps or from the risers directly onto the surface of the steps. In the particular embodiment of the invention by which I have chosen to illustrate this invention, I have provided a duct 48 35 extending lengthwise of the car between the two central cross sills 13 and 14 and just below the upper step 28 and in back of the riser 41 at the back of the lower step 25. The riser 41, which forms one of the side walls of the duct 48, is provided with apertures 42 adapted to direct the air 40 onto the surface of the lower step 25. If the riser 41 is made of sheet metal, the apertures 42 can be inverted louvres, as shown clearly in Fig. 3.

At the front of the car a diagonal partition 43 45 cuts off the corner of the space in the intersection of the front pier post 16 and the front cross sill 12. The partition 43 provides a passageway leading from the end of the warm air duct 10 to a duct 44 under the upper front step 38 and in 50 back of the riser between the steps 38 and 39. The duct 44 and the riser 45 are arranged in the same manner as the duct 48 and riser 41 in the steps at the center of the car.

With this arrangement, the steps 28 and 45 55 are warmed by the warm air passing in the ducts 48 and 44 under them, so that the small amount of snow which accumulates upon these upper steps will be melted. The snow which accumulates upon the lower steps 25 and 38 is melted by 60 direct contact with the warm air flowing out through the louvres 42 and 48 in the risers 41 and 45. The current of warm air also serves to some extent, to evaporate the moisture resulting from the melting of the snow, thus simultaneously drying the steps and increasing the humid- 65

ity inside of the car. The warm air directed inside of the stair wells by this arrangement mixes with the cold air which leaks in around the doors, warming it and preventing the portions of the car near the door from being chilled by the air 5 which has infiltrated.

While I have shown only the preferred embodiment of my invention, in which part of the energy dissipated as heat in the operation of a street car motor is used to melt the snow, my 10 invention, in its broader aspects, contemplates other sources of heat and other means of applying it and is limited only by the scope of the accompanying claims.

I claim:—

1. In a vehicle, an entrance or exit step, a wall rising above said step, a warm air chamber on the other side of said wall from said step, and apertures in said wall, said apertures being shaped so as to direct said warm air down upon 20 said step.

2. In a vehicle having a pair of hollow cross sills and steps between said cross sills, means for supplying warm air to the interior of said cross sills, and a duct below one of said steps, said 25 duct extending between and being connected to the interior of said sills, the top and one sidewall respectively of said duct forming the tread surface of one of said steps and the riser for the step therebelow, said riser having vents there- 30 through.

3. In a vehicle having a pair of hollow cross sills, means for supplying warm air to the interior of said cross sills, a step between said cross sills, a duct extending between said cross sills in 35 back of said step and means for discharging warm air from said cross sills onto said step.

4. In a vehicle having a hollow side sill forming a warm air duct of a heating and ventilating system, a hollow pier post and a hollow cross sill 40 forming a collecting air duct of said system, and an entrance or exit step on the other side of said pier post and cross sill from said side sill, the combination of a duct leading from the end of said side sill and under said pier post and said 45 cross sill and along the back of said step, and means for conducting air from said duct onto said step.

5. In a vehicle having a hollow side sill forming a warm air duct of a heating and ventilating 50 system, a hollow pier post and a hollow cross sill connected together at the end of said side sill and in line therewith and forming a return air duct, and an entrance step on the other side of said pier post and cross sill from said side sill, 55 the combination of a partition in the intersection of said pier post and side sill and sloping down towards the center line of the vehicle, said partition leaving the interiors of said pier post and said side sill in communication with each 60 other and defining a small separate chamber communicating with the end of said side sill, and means for leading air from said chamber onto said steps.
